UNITED STATES PATENT OFFICE.

FREDERICK SNARE, WOLFGANG G. TRIEST, AND JOHN ALEX. McNICOL,
OF NEW YORK, N. Y.

COALING-STATION OR STOREHOUSE FOR COAL, &c.

SPECIFICATION forming part of Letters Patent No. 731,965, dated June 23, 1903.

Application filed May 11, 1901. Serial No. 59,810. (No model.)

To all whom it may concern:

Be it known that we, FREDERICK SNARE, WOLFGANG G. TRIEST, and JOHN ALEX. McNICOL, citizens of the United States, residing 5 at New York city, in the county of New York and State of New York, have invented certain new and useful Improvements in Coal-ing-Stations or Storehouses for Coal, &c.; and we do declare the following to be a full, clear, 10 and exact description of the invention, such as will enable others skilled in the art to which it appertains to make and use the same, reference being had to the accompanying drawings, and to the figures of reference marked 15 thereon, which form a part of this specification.

Our invention relates to coaling-stations or storehouses for coal, &c.; and the objects of the same are to provide a strong and durable 20 building for storing coal, &c., and to provide means for conveying the coal to a point near the top of the building, where it is discharged through any one of a series of openings onto the floor of the building, there being a series 25 of tunnels underneath said floor to accommo-date cable-railways and hopper-like openings in said floor to expeditiously load cars when it is desired to convey the coal to a vessel for shipping.

30 Our coaling-station is designed to be erected on navigable streams and to be built in connection with a steel wharf or pier adapted to accommodate large coaling vessels. A cable-railway leads from the upper portion 35 of the pier to the top of the building, and the coal is loaded into dumping-cars and conveyed to the building and discharged therein. When it is desired to load other vessels or steamers with this coal, slide-doors under the 40 openings in the floor of the building are moved to one side and cars on cable-railways running in tunnels under the floor are loaded and taken out on the wharf and discharged into the vessel or steamer. One of the advantages 45 of this method of handling coal is the facility with which the coal may be stored and discharged. Another advantage of still greater importance resides in the fact that the coal is discharged from the bottom of the pile, and 50 in case of fire, which invariably starts at the bottom of the pile, the live coals can be quickly

removed and the great body of coal saved. In buildings as heretofore constructed it has been impracticable to reach the burning coal except by removing the great mass of coal 55 from the top of the pile until the fire was reached. We have provided means of ready access to the floor-line or bottom of the coal not only by a series of openings in the floor, but by providing openings and chutes at the 60 sides of the building, the floor being inclined at this point for discharging the coal by gravity through said openings in case of fire. We have also provided reliable and efficient means for ventilating and accurately deter- 65 mining the temperature at many different points within the pile of coal. To prevent the lower layer of coal from overheating, the cars under the floor may be loaded and conveyed to the top of the building and discharged in 70 order to effect a redistribution and conse-quent change of temperature. We have also made provision for storing a certain quantity of coal in bags for immediate use when re-quired. At convenient points under the floor 75 we have provided compartments for storing these bags and have made a convenient ar-rangement for the ready access by teams to said compartments.

We attain the objects and advantages above 80 referred to by means of the construction illus-trated in the accompanying drawings, in which—

Figure 1 is a transverse sectional elevation of a building constructed in accordance with 85 our invention. Fig. 2 is a sectional plan view on the line 2 2, Fig. 1. Fig. 3 is a transverse section taken through one of the hopper-like openings in the floor. Fig. 4 is a section on line 4 4, Fig. 3. Fig. 5 is a bottom plan view 90 of the sliding door for closing each of the hopper-like openings in the floor of the building.

In said drawings the numeral 1 designates the foundation-walls of the building, said walls being preferably of rubble and anchored 95 within a bed of cement filling. These walls are of a height to form tunnels 2 and compartments 3 under the floor of the structure.

The numeral 4 designates the lower floor of the building, said floor being constructed of strong metal girders resting upon the walls 1. At proper intervals in this floor hopper-like

openings 5 are provided, said openings being arranged centrally above the tunnels 2. As shown in Figs. 3, 4, and 5, these hopper-like openings in the floor rest upon I-beams and channel-irons, and the sides of the hoppers are bolted to flanges secured to the I-beams and to the sides of the hoppers. At the bottom of each hopper a pair of rails 6 are secured, and a sliding bottom 7 carries a series of rollers 8, mounted to move on the rails 6. A lever 9, fulcrumed at 10 to the bottom of the floor, is connected by a link 11 to the sliding bottom 7 for opening and closing the bottom of the hopper, as will be hereinafter described. The opposite sides of the floor 4 are somewhat inclined, as at 4^a, and the outside walls 1^a are provided with openings 1^b, which may be kept normally closed by slide-doors, constructed and operated similarly to the sliding bottom 7. A discharge-chute 1^c may be suspended by chains at the bottom of the openings 1^b to permit the coal to be discharged by gravity from the inclined portions 4^a of the floor in case of emergency. Immediately under the inclined portions 4^a of the floor are the compartments 3 for storing coal in bags for immediate use, and immediately adjoining these compartments the hopper-like openings in the floor are provided with sliding hoppers 13, designed for filling the bags 14 to be stored in the compartments 3.

A cable-railway system or any suitable means for quickly handling coal may be utilized. As shown, cable-railways pass through the tunnels 2 immediately under the hopper-like openings 5 in the floor 4.

The roof 15 of the building is constructed of strong metal beams and corrugated roofing plates, and the central upper floor 16 is supported upon heavy columns 16^a. A super-structure 17 covers this floor 16 to provide shelter for the incoming cars or conveyers. The floor 16 is formed of metal girders for supporting the railway-ties, the spaces between the girders and ties providing openings for discharging the coal, as shown at the right in Fig. 2. Cable-tracks 19 are supported upon the cross-ties, and dumping-cars 20 of any suitable construction may be utilized for conveying the coal from barges or vessels lying at the wharf. Spreaders 21 of strong sheet metal are hinged centrally under the openings in the floor to properly distribute the coal as it is discharged from the cars 20. The inclination of the spreaders 21 may be adjusted by means of chains 22, secured to said spreaders and passing up to a suitable winding mechanism. These spreaders may be mounted to slide on a guideway 23 in order that when it is desired to dump the coal directly through the openings between the girders the spreaders may be moved out of the way.

The building may be filled with coal to any desired height. For ventilating the coal-pile and for accurately determining the temperature at different points and at any height of the pile we have arranged a series of perfo-

rated metal pipes 24, properly braced from the columns and extending up through the body of the coal and down through the floor 4. At 70 the lower end of each pipe 24 a cap 25 is fitted, and if it is desired to take the temperature at any point a thermometer is inserted within the pipe and permitted to remain long enough to take the temperature, when it may 75 be withdrawn for inspection. Air passing in at the top of each pipe passes out through the perforations therein and circulates throughout the coal-pile.

From the foregoing it will be understood 80 that the coal is stored in the building by the incoming conveyers or cable-cars 20 and that the coal is discharged from the building at any time by the outgoing conveyers or cars under the floor in the tunnels 2, the bottom 7 85 being moved by the lever 9 to let the coal through. If the temperature of the coal rises to a degree beyond the safety-point, the lower layer may be removed by loading the cars through the floor-openings and running these 90 cars out and up to the top of the building and discharging them through the openings in the floor.

A very important feature of our invention resides in the facility with which the coal can 95 be reached in cases of fire or other emergency. The coal can be discharged through the hopper-like openings 5 into the cars and carried out, the openings 1^b can be utilized for discharging by gravity from the inclined portions 4^a of the floor, and teams may be used for carrying the bags of coal from the compartments 3. The means for ventilating and taking the temperature of the coal-pile are also important factors in an extensive coal plant. 105

What we claim as our invention is—

1. A plant for storing, and distributing coal, provided with a top floor, consisting of an open framework, permitting the passage of coal to the floor below; tracks on said floor extending lengthwise of the building; cars adapted to run on said tracks; a second floor, divided into horizontal solid sections, forming the floors of partitioned storage-chambers, extending the length of the building, each of said chambers having a series of hopper-shaped openings, and doors, extending longitudinally of the building beneath the tracks of top floor, and a third, or basement floor, beneath the second floor, having a series of tracks in alignment with the hopper-like openings, as herein set forth.

2. A plant for storing, and distributing coal, provided with a top floor, consisting of an open framework, permitting the passage of coal to the floor below; tracks on said floor, extending lengthwise of the building, cars adapted to run on said tracks; a second floor, divided into horizontal solid sections, forming the floors of partitioned storage-chambers, and having a series of hopper-shaped openings, and doors, extending longitudinally of the building beneath the tracks of top floor; inclined floors at the sides of the second floor;

- hopper-shaped openings, or chutes, and doors, in the sides of the building, opposite said inclined side floors; a third, or basement floor, beneath the second floor, having a series of 5 tracks in alignment with the hopper-like openings; and bins, or storage chambers at the sides of the basement-floor, as herein set forth.
3. A storehouse comprising a lower floor, and an upper floor provided with discharge- 10 openings, a railway-track supported upon said upper floor, and spreaders supported below the openings in the upper floor.
4. In a storehouse for coal, a series of vertically-arranged pipes extending through the 15 coal-pile and through the floor of the building, caps for covering the lower ends of the pipes, ventilating openings in the pipes, and means for admitting a thermometer within
- the pipes to determine the temperature of the coal at different points, substantially as described. 20
5. A storehouse comprising a lower floor, and an upper floor provided with discharge-openings, a railway-track supported upon said upper floor, hinged spreaders supported 25 below the openings on the upper floor, and means for adjusting said spreaders.

In testimony whereof we affix our signatures in presence of two witnesses.
